Primary Examiner — Cynthia Ramirez*Assistant Examiner* — Gino Colan(74) *Attorney, Agent, or Firm* — Edwards Wildman Palmer LLP; George N. Chaclas(57) **CLAIM**

The ornamental design for a cartridge check assembly, as shown and described.

DESCRIPTION

FIG. 1 is a top perspective view of the cartridge check assembly according to the present disclosure.

FIG. 2 is another perspective view of the cartridge check assembly according to the present disclosure.

FIG. 3 is a front view of the cartridge check assembly according to the present disclosure.

FIG. 4 is a back view of the cartridge check assembly according to the present disclosure.

FIG. 5 is a right side view of the cartridge check assembly according to the present disclosure.

FIG. 6 is a left side view of the cartridge check assembly according to the present disclosure.

FIG. 7 is a top view of the cartridge check assembly according to the present disclosure; and,

FIG. 8 is a bottom view of the cartridge check assembly according to the present disclosure.

1 Claim, 8 Drawing Sheets(56)
